UNITED STATES PATENT OFFICE.

EUGENE CLAYTON BERNHEIM, OF WASHINGTON, DISTRICT OF COLUMBIA, ASSIGNOR TO JOHN H. FLANAGAN, OF SAME PLACE.

DESIGN FOR A SPOON.

SPECIFICATION forming part of Design No. 22,082, dated December 27, 1892.

Application filed November 21, 1892. Serial No. 452,733. Term of patent 3½ years.

To all whom it may concern:

Be it known that I, EUGENE CLAYTON BERNHEIM, a citizen of the United States, residing at Washington, in the District of Columbia, have invented and produced a new and original Design for a Souvenir Spoon; and I do hereby declare the following to be a full, clear, and exact description of the same, reference being had to the accompanying drawing, forming a part thereof.

The accompanying drawing which forms a part of this specification represents a spoon possessing the characteristic features which comprise the design.

The leading or characteristic features of this design, are a conventionalized bust portrait of the President elect on the outer extremity of the handle of a spoon, and in the bowl of which is a representation of the east front of the National Capitol, on the occasion 20 of administering the oath of office to the President elect.

The handle or stem of the spoon is composed on a streamer of the national flag, on a portion of which is arranged a scroll bearing 25 any suitable or desired inscription.

This design for a spoon is intended as a souvenir for inaugural occasions.

What I claim as my design, and desire to protect by Letters Patent is.

The design for a spoon, substantially as herein shown and described.

In testimony whereof I affix my signature in presence of two witnesses.

EUGENE CLAYTON BERNHEIM.
